DESIGN FOR A PAIR OF SPECTACLES

Reuben Myers, Southport, England, assignor, by mesne assignments, to Plastispec Incorporated,
New York, N. Y., a corporation of New York

Application May 22, 1946, Serial No. 129,974

Term of patent 14 years

(Cl. D57—1)

To all whom it may concern:

Be it known that I, Reuben Myers, a citizen of Great Britain, residing at Southport, Lancashire, England, have invented a new, original,
and ornamental Design for a Pair of Spectacles,
of which the following is a specification, reference being had to the accompanying drawing, forming part thereof.

In the drawing

Fig. 1 is a front perspective view of a pair of spectacles, showing my new design.

Fig. 2 is a top view thereof.

I claim:

The ornamental design for a pair of spectacles,
as shown.

REUBEN MYERS.
